US00D357672S

United States Patent [19]

Terasawa et al.

[11] Patent Number: Des. 357,672

[45] Date of Patent: ** Apr. 25, 1995

[54] HYBRID INTEGRATED CIRCUIT FOR ELECTRIC POWER CONTROL

[75] Inventors: Noriho Terasawa; Shin Soyano, both of Kanagawa, Japan

[73] Assignee: Fuji Electric Co., Ltd., Kanagawa, Japan

[**] Term: 14 Years

[21] Appl. No.: 19,287

[22] Filed: Feb. 28, 1994

[30] Foreign Application Priority Data

Sep. 16, 1993 [JP] Japan 5-27994

[57] CLAIM

The ornamental design for a hybriic integrated circuit for electric power control, as shown.

DESCRIPTION

FIG. 1 is a perspective view of the top, front and right side of a hybrid integrated circuit for electric power control showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

FIG. 1

FIG. 2

*FIG. 3**FIG. 4**FIG. 5**FIG. 6**FIG. 7*
